UNITED STATES PATENT OFFICE

2,450,844

REFRIGERATOR PROVIDED WITH A
REFRIGERATED DRAWER

Fred W. Stuart, Cincinnati, Ohio

Application December 13, 1944, Serial No. 567,979

16 Claims. (Cl. 62—116)

1

The present invention relates to household type refrigerators and is particularly directed to improvements in this type of refrigerator which have special food storage compartments wherein substantially low temperatures, approximating 0° F., are maintained for keeping food in a frozen state for indefinite periods of time.

An object of the invention is to provide in a refrigerator a food compartment which is entirely independent of the normal food compartment therefor and which has improved means for permitting access to its food storage compartment.

Another object of the invention is to provide a low temperature food storage compartment which is mounted for sliding movement within the refrigerator cabinet and which has a removable top by which access is had to the interior of said compartment.

A further object of the invention is to provide a reliable and simplified means for transmitting refrigerant between a stationarily mounted refrigerating unit and a sliding compartment for the storage of food at substantially low temperatures.

A still further object of the invention is to provide in a refrigerator cabinet means for accommodating the refrigerant transmitting tubes which interconnect a refrigerating unit and a sliding, low temperature compartment which has disposed therebetween the normal food storage compartment.

Other objects will be apparent from the following specification and drawings wherein the preferred embodiments of my invention are set forth, and in which:

Fig. 1 is a fragmental, side elevational view of a refrigerator, parts thereof being shown in cross-section.

Fig. 2 is a fragmental view taken on line 2—2 of Fig. 1.

Fig. 3 is a cross-sectional view taken on line 3—3 of Fig. 1.

Fig. 4 is a fragmental, side elevational view of a modified form of my refrigerator.

Fig. 5 is a cross-sectional view taken on line 5—5 of Fig. 4.

Fig. 6 is an enlarged, cross-sectional view taken on line 6—6 of Fig. 5.

The embodiment of my invention consists of a refrigerator cabinet 10 which has a centrally disposed chamber 11 for the normal storage of foods at relatively low temperatures. This cabinet is formed in the conventional manner with heat insulating side walls 12 and 13, a rear wall 55

14 and top and bottom walls 15 and 16 respectively. Shelves 160 are mounted within the chamber 11 and food stored thereupon is accessible from the exterior of the cabinet by means of a hinged door 17 which is also constructed in the usual manner of heat insulating material.

The refrigerator has the usual sheet metal walls protecting the insulation in the normal food compartment and all of these outer walls for the compartment extend to, or near, the floor except the sheet metal side wall 18 (Fig. 2) which terminates just beneath the bottom wall 16 of the chamber. The sheet metal wall 19 for the chamber wall 12 and the sheet metal wall 20 for the rear wall 14 form with a spaced wall 21, a lower compartment for housing a sliding drawer 22. This drawer has a front wall 23, back wall 24, side walls 25 and 26 and a bottom 27 all constructed of metal armored heat insulating material, said drawer being mounted on rollers 28 for sliding movement in and out of the cabinet compartment. The rollers are rotatably mounted on lower guides 29 and 30, said guides taking the form of angle irons having their bases welded or otherwise fastened to a bottom wall 31 of the cabinet. A stop 32 projects upwardly from the bottom wall 31 and cooperates with a lug 33 depending from the rear wall of the drawer, for limiting the outward movement of the drawer when it is manually slid to open position by means of a handle 34.

An open topped compartment 35 is formed by the side, end and bottom walls of the drawer and the side walls for the compartment are lined with a hollow casing 36 for housing an evaporator 37. The compartment is closed by a lid 38 comprising two sections 39 and 40 connected along their transverse adjacent edges by a hinge 41. When it is desired to obtain frozen food from the storage compartment 35, the drawer is rectilinearly slid outwardly so that the door 40 is outside of the body of the cabinet whereupon said door section may be manually rotated upwardly on the hinge 41 for access into said compartment. It will be noted that access to this low temperature storage compartment is wholly independent of the normal food storage chamber and that when the low temperature storage compartment is opened, from the top only, it precludes the entrance of warm air therein because said warm air being lighter than the cold air in the compartment, will not displace said heavier air and therefore does not enter the compartment.

Refrigerant under pressure is introduced to

the evaporator 57 through an expansion valve, or restricted orifice, 42 which is rigidly mounted on the outside of the sliding drawer 22 and extends into a vertically extending passageway 43 formed by the metal walls 18, 20 and 21 and a narrow front wall 44 (Fig. 3). This valve is connected to one end of the evaporator coil by an elbow 45 and a short pipe connection 46. Reduced pressure refrigerant leaves the evaporator coil through an elbow connection 47, which is mounted on the side of the drawer and which also extends into the vertical passageway.

Refrigerant is supplied to the evaporator in the sliding drawer compartment by means of a conventional refrigerating unit 48 which may be of the compressor or absorption type. The drawings illustrate a compressor unit which has a motor driven compressor 49 connected on its pressure side by a pipe line 50 to a condenser 51. Cooled refrigerant under pressure is directed to a rigidly mounted coupling 52 by a pipe 53, said coupling extending into the upper portion of the passageway 43. A flexible tubing 54 is fastened at its upper end to the coupling 52 and is connected at its lower end to the expansion valve 42. The tubing has a length greater than the straight line distance between the coupling and the valve in all their relative positions, and its length is disposed within the passageway and out of contact with the sheet metal walls as is most clearly illustrated in Fig. 2. A lower pressure refrigerant is returned from the evaporator coils through the flexible tubing 55 which is connected at its lower end to the elbow 47 and at its upper end to a stationarily mounted coupling 56 fastened to the end of a pipe 57 which extends from the side wall of the normal food storage compartment and is connected at its inner end to an expansion valve, or a restrictive orifice, 58 on the evaporator 59 for said normal food storage chamber. A refrigerant return pipe 60 is connected between the evaporator 59 and the compressor 49.

The upper portions of the sheet metal walls 19 and 21 and the front wall 61 are joined along their upper edges to a top sheet metal wall 62 which forms therewith a housing for the compressor and condenser unit of the refrigerating system.

The flexible tubing may have a braid wire armor which protects a flexible metal or synthetic type tubing having neutral characteristics relative to the type of refrigerant used in the system. It will therefore be noted that the sliding movement of the compartment relative to a stationarily mounted refrigerating unit is permitted by the loose connection of the flexible tubing between the unit and the compartment and said tubing will not be worn, damaged or fatigued during the relative movement between said unit and the compartment because it is freely hung within the passageway 43. As illustrated in Fig. 1, this tubing has a substantially flattened S-shape in side elevation and its body portion is disposed in a transverse plane extending through the approximate center of the passageway 43 (Fig. 2).

The modification of my refrigerator illustrated in Figs. 4-6 of the drawings has a centrally disposed normal food storage chamber 63 similar in all respects to that illustrated for the refrigerator shown in Figs. 1-3. A compressor and condenser unit is mounted upon the top wall 64 of the chamber and a low temperature, food compartment 65 is disposed within a sliding drawer 66 which in turn is positioned beneath the normal food compartment also in a manner similar to

that illustrated in Figs. 1-3. An evaporator 67 surrounds the low temperature food compartment 65, and the ends of coils 68 therefor being connected to pipes 69 and 70 which in turn communicate with coupling members 71 and 72 respectively fastened to the back wall 73 of the drawer by bolts 74 (Fig. 6). The usual refrigerant restrictive device 75 is interposed in the pressure pipe 69.

10 High pressure and reduced pressure refrigerant service pipes 75 and 76 respectively communicate with the refrigerating unit in the manner illustrated in Figs. 1-3 and are each connected at their lower ends, to stationarily mounted coupling members 77 and 78, said coupling members co-operating with couplings 69 and 70 to transmit refrigerant to and from the evaporator. These stationary coupling members are fastened to a rear sheet metal wall 79 of the refrigerator by bolts 180. This rear wall forms with the rear wall of the normal food chamber and the sheet metal side walls 80 and 81, a vertically extending passageway 82 through which the refrigerant pipes 75 and 76 pass, as is most clearly illustrated in Figs. 4 and 5.

15 The cooperative coupling members 71-77 and 72-78 are similar in construction. I shall therefore describe the former members with particular reference to Fig. 6 of the drawing. Broadly, these 20 cooperative coupling members function to automatically close shut-off valves in each of them when the low temperature food storage drawer 66 is initially moved in a rectilinear direction toward its open position within the cabinet. The coupling member 71 therefore consists of a block 83 which has encircling its end, a telescopic member 84 urged outwardly from the block by means of a spring 85 which bears, at its inner end, against a disc 86 bolted to the block, and at its outer end, 25 against a seat member 87 bolted to a flange 88, the latter being formed on the outer periphery of the telescopic member 84. A shoulder 89 is formed on the interior of the telescopic member and forms a limit stop for the latter member 30 against the action of spring 85. The refrigerant pressure line 75 communicates with a chamber 90 formed centrally in the block 83, said chamber having a tapered seat 91 formed therein which 35 cooperates with a tapered valve head 92, disposed within said chamber. The valve head has a stem 93 integrally fastened thereto and which moves in a guideway 94, formed in a plug 95. The passageway is sealed by the threaded plug 95 and a relatively heavy compression spring 96 is disposed 40 within the chamber and acts to urge the valve 92 against its seat 91 to preclude the passage of high pressure refrigerant from the chamber. A refrigerant passageway 97 is formed in the forward end of the block and communicates with the chamber 90, said passageway being continued 45 to an exterior seat 98 formed in the seat member 87 by means of a bellows 99 which is placed under compression between the disc 86 and a shoulder 100, formed on the seat member 87.

50 The cooperating, movable coupling member which is fastened to the drawer comprises a block 101 which has a tapered nose portion 102 for detachable engagement with the tapered seat 98. A tapered valve 103 is guided for reciprocating motion within the nose by a stem portion 104 moving at its rear end in a hole 105 formed in an exteriorly threaded screw plug 106. The valve is urged toward its seat by a light compression spring 107 and refrigerant is permitted to pass 55 by the valve when it is moved from its seat

through ports 108 formed in the plug and thence through the refrigerant pipe 69. A valve actuating rod 108 is rigidly fastened at its one end to the valve 92 and extends therefrom through the passageway 91 and functions to contact the valve 103 at its outer end to open both of said valves.

To maintain the drawer 66 in its closed position, a suitable positive acting latch 110 is rotatably mounted in the upper portion of the drawer front wall. This latch may take the form of eccentric cam 111, which upon manual rotation is engaged in a slot 112, formed in the cabinet wall. To preclude excessive pressures in the refrigerant pressure line 75 after the drawer has been withdrawn from its normal position, an electric switch 113 is stationarily mounted at the rear of the drawer 66, said switch being connected in series in the circuit for the motor 114 which drives the compressor 115. In the event an absorption type refrigerating unit is employed, a suitable by-pass actuating means could be substituted for the switch 113. To this end the two circuit lines 116 and 117 are led from the refrigerating unit through the passageway 82, within a cable 118, the circuit lines being connected to a conventional outlet plug 119, said circuit line 117 having interposed therein a compressor fan motor 120 and the motor 114. An arm 121 for the switch is spring urged to open the switch and when the drawer 66 is moved to its normal latched position within the refrigerator the switch arm is rotated counter-clockwise to close the motor circuit.

It will therefore be noted that when the coupling members are out of engagement with each other, that is, when the tapered nose 102 is detached from the tapered seat 98, valve 92 will be in contact with seat 91 by action of its spring 96, whilst the valve 103 will be in engagement with its seat by action of its spring 107. The initial movement of the drawer 66 toward its open position will uncouple the members and cause their respective valves to assume their closed positions. In this condition refrigerant is precluded from passing through the lines 75 and 76, and refrigerant in the evaporator can not escape therefrom.

Upon closing the drawer the tapered nose 102 first contacts and seats against the tapered opening 98 in seat member 81 and during the intermediate movement of the drawer to its closed position, the telescopic member slides back on the block 83 against the action of spring 85 to thereby seal the refrigerant line through the coupling prior to the opening of the valves 92 and 103. While this action is occurring, the rod 109 contacts the valve 103 and due to the fact that its spring 107 is lighter in action than the spring 96, said valve 103 will first be opened. Further movement of the drawer will cause the valve stem 104 to stop against the bottom of the hole 105 whereupon further movement of the drawer will open the valve 92 against the action of spring 96 which permits the transmission of refrigerant under pressure between the pipes 69 and 75.

What is claimed is:

1. In a device of the class described the combination of a refrigerating unit, a sliding compartment disposed in vertical, spaced relationship with the unit, a refrigerant evaporator in the compartment, a direct refrigerant expansion means affixed to the compartment and connected to the evaporator, and refrigerant transmitting

means between the unit and the evaporator for permitting sliding movement of the compartment.

2. In a device of the class described the combination of a refrigerating unit, a normal food storage chamber, a sliding compartment for low temperature food storage, a refrigerant evaporator in the compartment, refrigerant transmitting means between the unit and the evaporator for permitting movement of said compartment relative to the unit, and a direct expansion means affixed to the compartment and interposed between the evaporator and the refrigerant transmitting means.

15 3. A refrigerator having a normal food storage chamber, a housing upon the chamber, a refrigerating unit mounted within the housing, a compartment for low temperature food storage, means for mounting said compartment beneath the chamber for sliding movement, a refrigerant evaporator in the compartment, and refrigerant transmitting means between the unit and the evaporator for permitting sliding movement of the compartment.

20 4. A refrigerator having a normal food storage chamber, a housing upon the chamber, a refrigerating unit mounted in said housing, a compartment for low temperature food storage disposed beneath the chamber and wholly independent therefrom, means for mounting the compartment for sliding movement, a vertically extending passageway between the housing and an exterior side of the compartment, a refrigerant evaporator in the compartment, and refrigerant transmitting means between the evaporator and the unit disposed in the passageway and permitting sliding movement of the compartment.

25 5. A refrigerator having a normal food storage chamber, a refrigerating unit upon the chamber, a sliding drawer disposed beneath the chamber, a low temperature food compartment in the drawer, a refrigerant evaporator in the compartment, and a flexible tubing between the unit and the evaporator for transmitting refrigerant therebetween.

30 45 6. A refrigerator having a normal food storage chamber, a refrigerating unit, a housing for the unit, a sliding drawer disposed beneath the chamber, a low temperature food compartment within the drawer, a refrigerant evaporator for the compartment, a vertical passageway disposed on one side of the chamber and extending between the housing and the drawer, a flexible tubing freely disposed within the passageway and connecting the unit to the evaporator for transmitting refrigerant therebetween.

35 50 7. A refrigerator having a normal food storage chamber, a refrigerating condenser and compressor unit mounted upon the chamber, a housing for the unit, a sliding drawer disposed beneath the chamber, a low temperature food compartment within the drawer, a refrigerant evaporator surrounding the compartment, a vertical passageway disposed on one side of the chamber and extending between the housing and the drawer, a flexible tubing freely disposed within the passageway and connecting the unit to the evaporator for transmitting refrigerant therebetween.

40 55 8. A refrigerator having a normal food storage chamber, a housing disposed above the chamber, a refrigerating unit in the housing, a drawer mounted for horizontal, rectilinear movement beneath the chamber, a relatively deep, vertical passageway disposed on one side of the chamber and having its depth dimension parallel to the 60 65 direction of movement of the drawer, a low tem-

70 75 75 75

perature food compartment within the drawer, an evaporator in the compartment, a refrigerant coupling for the evaporator depending centrally into the lower portion of the passageway, a refrigerant coupling connected to the unit and extending into the upper portion of the passageway, and a flexible tube connected to the two couplings and held thereby within the said passageway.

9. A refrigerator having a normal food storage chamber, a housing disposed above the chamber, a refrigerating unit in the housing, a drawer mounted for horizontal, rectilinear movement beneath the chamber, a relatively deep, vertical passageway disposed on one side of the chamber and having its depth dimension parallel to the direction of movement of the drawer, a low temperature food compartment within the drawer, an evaporator in the compartment, a refrigerant coupling for the evaporator extending into the lower portion of the passageway, a rigid refrigerant coupling connected to the unit and extending into the upper portion of the passageway, and a flexible tube connected to the two couplings and held thereby within the said passageway, said flexible tube having a length greater than the straight line distance between the couplings.

10. A refrigerator including a refrigerant transmitting pipe, a sliding drawer, a food compartment in the drawer, an evaporator for the compartment, a stationary coupling for the pipe, a coupling for the evaporator mounted on the drawer and adapted to engage the stationary coupling when the drawer is in its closed position, a shut-off valve for each coupling, means for urging said valves to closed positions, and means for maintaining the valve in open positions when said drawer is in its closed position.

11. A refrigerator including a refrigerant transmitting pipe, a sliding drawer, a food compartment in the drawer, an evaporator for the compartment, a two-part coupling between the evaporator and the pipe, a shut-off valve in each coupling part, and means for maintaining the valves in open position when the drawer is closed.

12. A refrigerator including a stationary refrigerant transmitting pipe, a slideable food compartment, an evaporator for the compartment, a two-part coupling between the pipe and the evaporator, detachable cooperating means between the two parts for engaging them upon movement of the compartment to its closed position within the refrigerator, a shut-off valve in each part, means for automatically closing the valves when the two parts are in disengaged positions, and means for opening said valves when the parts are in engaged positions.

13. A low temperature, food storage compartment for a self-contained, mechanical refrigerator having a refrigerating unit mounted thereon comprising insulated side, end and bottom walls forming an open-topped compartment, a refrigerant evaporator within the compartment, direct expansion means affixed to the compartment and communicating with one end of the evaporator, return suction means mounted on a wall of the compartment and connected with the opposite end of the evaporator, conduit means for connecting the direct expansion means and the return suction means to the refrigerating unit, and means for guiding the compartment for rectilinear movement into and out of the refrigerator.

14. A low temperature, food storage compartment for a self-contained mechanical refrigerator

having a refrigerating unit affixed thereto comprising insulated side, end and bottom walls forming an open-topped compartment, at least one of said walls having an evaporator aperture formed therein and disposed adjacent the interior surface of said compartment wall, a direct expansion means affixed to the compartment and in communication with one end of the evaporator aperture, a return suction fitting fixed to a compartment wall and connected with the opposite end of the evaporator aperture, conduit means connecting the direct expansion means and the return suction fitting to the refrigerating unit, and means for guiding the compartment for rectilinear movement into and out of the refrigerator.

15. In a device of the class described the combination of a non-insulating cabinet casing having a top wall, a bottom wall and side and end walls, a closed, insulated chamber for normal food storage fixed centrally within the cabinet casing and forming with the cabinet casing walls upper and lower housing sections, said chamber having an opening therein for access to its interior, an insulated closure for the opening, said compartment having one side wall disposed in spaced relation with an adjacent side wall of the cabinet casing to form a vertical passage between the sections, a compressor unit for the chamber mounted within one section, an open-topped sharp freeze drawer disposed for sliding movement within the other section, said drawer having insulated side, bottom and end walls, an insulated closure for the drawer top, a refrigerant evaporator unit lining the interior surface of the drawer walls, and refrigerant transmitting means between the evaporator unit and the compressor unit, said means being disposed and freely movable in the vertical passage.

16. In a device of the class described the combination of a non-insulating cabinet casing having a top wall, a bottom wall and side and end walls, a closed, insulated chamber for normal food storage fixed centrally within the cabinet casing walls and forming with the cabinet casing walls upper and lower housing sections, said chamber having an opening therein for access to its interior, an insulated closure for the opening, said chamber having one side wall disposed in spaced relation with an adjacent side wall of the cabinet casing to form a vertical passage between the sections, a compressor unit for the chamber mounted within one section, an open-topped sharp freeze drawer disposed for sliding movement within the other section, said drawer having insulated side, bottom and end walls, a refrigerant evaporator unit lining the interior surface of the drawer walls, and refrigerant transmitting means between the evaporator unit and the compressor unit, said means being disposed and freely movable in the vertical passage.
